HYDRAULIC ACTUATING MECHANISM FOR
STOKERSRoyce L. Beers, Birmingham, Mich., assignor to
Detroit Stoker Company, Monroe, Mich., a cor-
poration of Michigan

Application June 26, 1939, Serial No. 281,302

4 Claims. (CL. 121—157)

The invention relates to stokers of that type in which the fuel is periodically fed into the furnace by the operation of a fuel pusher or ram. More particularly, the invention relates to the means for operating the ram and has for its object the obtaining of a simple construction having certain advantages over and avoiding certain defects of constructions heretofore used for this purpose. To this end the invention consists: first, in the peculiar construction of the hydraulic actuating mechanism; second, in the means for variably timing the operating cycles independently of the speed of movement of the ram; third, in the means for guarding against danger of breakage of the parts in case of obstruction to the feed; fourth, in the means for maintaining the device operative, at least to some extent, even where there is partial obstruction to the feeding; fifth, in various other advantageous features as hereinafter set forth.

In the drawings:

Figure 1 is a vertical longitudinal section through the fuel feeder and hydraulic actuating mechanism;

Figure 2 is a cross section partly in elevation;

Figures 3 and 4 are diagrammatic views respectively in longitudinal section and cross section.

The stoker to which my improvements are applied may be of any suitable construction such as illustrated and which includes a hopper or storage receptacle A for the fuel, a ram B arranged beneath this hopper in alignment with a fuel feeding aperture C entering the furnace, said ram being normally positioned to close communication between said aperture and hopper, and a frame D in which said ram is slidably mounted. My improved hydraulic actuating mechanism is mounted on this frame and is of the following construction. E is a cylinder block secured to the outer end of the frame D and having a bore F for a piston G which is directly connected by a piston rod H to the ram B. Above the bore F and preferably parallel thereto is a second bore having a small diameter cylindrical portion I and a larger diameter cylindrical portion I'. Within the large diameter portion is a valve J which controls passages K and K' leading respectively to the outer and inner ends of the cylinder F and also an intermediate exhaust passage K². A drain passage K³ connects to the outer end of the small diameter cylinder I. Below the bore F and extending upward on opposite sides of the same within the block E is a storage chamber L for hydraulic fluid. A second and separate chamber L' is formed within the block above the large diameter cylinder portion I' and communicating to the inner end thereof through a port L². M and M' are pistons respectively within the

small and large diameter bores I, I', said pistons being connected to each other by a rod M². This rod passes through a bearing in the valve J while the pistons M and M' impinging against the opposite ends of said valve form a lost motion actuating means therefor.

The hydraulic fluid for actuating the pistons is preferably supplied by a pump of the type which maintains a substantially uniform discharge pressure with a variable volume corresponding to demand. The specific construction of this pump forms no part of the present invention and it is, therefore, merely indicated diagrammatically. As shown, the pump N is mounted on top of the block E and is connected by a suction conduit N' with the bottom of the storage chamber or sump L. A screen or filter N² surrounding the lower end of said conduit serves to prevent the entrance of dirt or sediment into the pump. The discharge conduit N³ of the pump is connected directly to the chamber L' so as to maintain in this chamber and also in the connected large cylinder portion I' a predetermined pressure, such for instance as two hundred and fifty pounds per square inch.

With the construction as thus far described, it will be evident that the fluid pressure within the cylinder I' acting upon the two pistons M and M' will through the differential areas thereof force said pistons to the right, Figure 1, and will move the valve J to a position where fluid is admitted to the passage K and from the latter into the outer end of the cylinder F. This will move the piston G forward and through the rod H will move the ram B to its normal position beneath the hopper A. To retract the ram the valve J must be shifted so as to admit fluid through the passage K' to the inner end of the cylinder F while the passage K leading to the outer end will simultaneously be connected to the exhaust K² which empties into the sump or chamber L. For accomplishing such movement I have provided restricting means for admitting fluid to the cylinder I' on the opposite side of the piston M'. This will slowly move the pistons M and M' to the left, Figure 1, and near the completion of the movement the piston M' impinging against the valve J, will shift the latter. Any leakage of fluid past the piston M will escape through the drain passage K³. During the interval in which the pistons are moving prior to contact with the valve, the ram remains stationary in its forward position. When, however, the valve is shifted the ram will be quickly retracted. A reshifting of the valve to its original position is then accomplished by exhausting the fluid forward of the piston M', which in turn is effected by a valve O having its operating stem extending into the path of the ram. As shown, this valve is located in a casing P at the forward

end of the block E, a spring O' normally holding the valve to its seat and the stem O² being actuated by the ram to unseat the valve. An exhaust port P' leading to the sump is opened by the unseating of the valve with the result that the pistons M and M' quickly move forward under the actuation of the differential fluid pressure. Thus, the valve J is restored to its normal position in which fluid is admitted to the outer end of the cylinder F to drive the piston G and ram B forward, which completes the cycle.

From the description given, it will be evident that the length of period of rest of the ram is dependent upon the degree of restriction which controls the rate of fluid flow into the right hand end of the cylinder I', and consequently the time required for its movement rearward into contact with the valve J. On the other hand, the speed of operation of the ram is determined only by the fluid pressure, the size of the ports and passages and the resistance to be overcome. It is, therefore, possible in designing the construction to have the ram always operate at a desirable speed and at the same time to control the fuel feed by altering the length of intervals between successive operations. For such control I preferably employ a regulating valve Q, which is placed in a conduit R leading from the conduit N³ to the valve casing P, which latter has a passage P² extending to the right hand end of the cylinder I'. The valve Q may be of any suitable construction by means of which the flow of fluid therethrough may be graduated, so that by shifting the actuating handle Q' the operator may increase or decrease the timing as desired.

In the operation of a stoker it sometimes happens that the fuel feed will become clogged so as to endanger breakage of parts. Usually this is guarded against by the use of a shearing pin in some portion of the mechanism, which in case of an overload will be severed, rendering the apparatus temporarily inoperative. With my construction the maximum actuating force is determined by the constant fluid pressure and the area of the piston in the hydraulic motor, this force being limited to avoid danger of breakage. Thus, should an obstruction to the fuel feed occur before completion of the forward stroke of the ram further forward movement will be arrested. However, this does not render the device inoperative, for at the completion of the time interval the motor and ram will be moved rearward and then forward again to the same point. In other words, instead of completely stopping the fuel feed the stroke of the ram is merely shortened.

What I claim as my invention is:

1. In a stoker, the combination with a fuel feeding ram, of a reciprocatory hydraulic motor directly connected therewith to retract the ram by its rear stroke and to feed the fuel by its forward stroke, means for supplying fluid to said motor at a substantially constant predetermined pressure, a valve controlling the reciprocations of said motor automatically quickly reversed at the completion of said rear stroke, a member actuated by hydraulic pressure having a lost motion connection to said valve, means operating at the beginning of the forward stroke of said motor for supplying the actuating fluid to said member to move it in one direction, means for moving said member in the other direction, and adjust-

able means for regulating the rate of supply and thereby controlling the timing of successive cycles of said motor and ram.

2. In a stoker, the combination with a fuel feeding ram, of a reciprocatory hydraulic motor directly connected therewith to retract the ram by its rear stroke and to feed the fuel by its forward stroke, means for supplying fluid to said motor at a substantially constant predetermined pressure, a valve for controlling said motor, hydraulic actuating means for said valve having a lost motion connection therewith and normally held by differential pressure to position said valve for the forward movement of said motor, means automatically operating upon the beginning of the forward stroke of said motor for supplying fluid to said hydraulic actuating means so as to reverse the differential pressure thereon and to effect a movement thereof in the opposite direction, means for regulating the rate of supply to time the interval for taking up lost motion and actuating said valve so as to cause a rear stroke of said motor, and means operating upon the completion of said rear stroke for exhausting the fluid from said regulated supply to again reverse the differential pressure on said actuating means, whereby said valve is quickly reversed for the forward stroke of said motor and ram.

3. In a stoker, the combination with a fuel feeding ram, of a reciprocatory hydraulic motor directly connected therewith to retract the ram by its rear stroke and to feed fuel by its forward stroke and controlling means for said motor comprising aligned communicating cylinders of different diameters, connected spaced pistons in the respective cylinders, means for supplying to the space between said pistons hydraulic fluid at substantially constant pressure, a valve located in the space between and having a lost motion connection with said pistons, said valve controlling ports to the opposite ends of said motor, the differential area of said pistons normally holding said valve in a position for the forward stroke of said motor, means for supplying fluid to said large cylinder on the opposite side of said piston to move the same in reverse direction, means for regulating the rate of flow of the supplied fluid to vary the interval in which lost motion is taken up and said valve is actuated, a pilot valve opened at the completion of the rear stroke of said motor for exhausting said supplied fluid and to permit the quick operation of said pistons to reverse said first mentioned valve, and means for closing said pilot valve at the beginning of the forward stroke of said motor and ram.

4. In a stoker, the combination with a fuel feeding ram, of a reciprocatory hydraulic motor directly connected therewith to retract the ram by its rear stroke and to feed the fuel by its forward stroke, means for supplying fluid to said motor at a substantially constant predetermined pressure, a valve for controlling said motor, means for quickly reversing said valve at the completion of the rear stroke of said motor for effecting a forward stroke thereof, and means operating after a predetermined time interval from the beginning of the forward stroke of said motor for again reversing the valve to cause a rear stroke.
